UNITED STATES PATENT OFFICE.

ANDREW J. DOANE, OF INDIANAPOLIS, INDIANA.

SAW-HANDLE.

SPECIFICATION forming part of Letters Patent No. 250,217, dated November 29, 1881.

Application filed July 27, 1881. (No model.)

To all whom it may concern:

Be it known that I, ANDREW J. DOANE, a citizen of the United States, residing at Indianapolis, in the county of Marion and State 5 of Indiana, have invented a new and useful Improvement in Ferrules with Swiveled Clamp-Plate for Crosscut-Saw Handles, of which the following is a specification.

Heretofore saw-handles have been provided 10 with a hollow plug for securing the nut in which works the threaded end of a slotted bolt that holds the saw, the lower end of the handle having a ferrule provided with an integral exterior flange to receive the lugs of a movable washer 15 or swiveled section, which lugs are turned up over said flange. This washer is also hollowed out to accommodate the projecting end of the interior plug, and is grooved or provided with 20 guide-lugs on its under surface, to receive the saw-plate. The several parts of the ferrule as thus made, however, have been formed separately, the lower section or washer being afterward attached to the ferrule proper by bending the lugs or flange of the washer over the 25 annular head or flange of the ferrule. To do this safely the washer must be made of wrought or malleable metal, and thus involves considerable expense in time and material.

My invention obviates these difficulties, and 30 relates to improvements in ferrules with swiveled clamp-plate for crosscut-saw handles, in which the socket-section of the ferrule operates in conjunction with a swiveled section; and the object of my invention is to provide a 35 socket-ferrule for crosscut-saw handles, with a swivel saw-clamping section cast thereon. This object I accomplish by the device illustrated in the accompanying drawings, in which—

Figure 1 represents a view of the saw-clamp 40 end of the swivel-section. Fig. 2 is a section of the entire device, showing the manner in which the two sections of the ferrule are united together and the manner in which a saw-blade is made fast to the handle.

45 A represents an ordinary crosscut-saw handle with stationary nut D, hole B, and saw-holding loop I.

The section E is cast with a recess to receive the end a of the handle A, and a chamber, b, 50 below to permit the upper end of the loop I to enter. The outer surface of the section E is

provided with a groove, G, which extends all around the ferrule, near its lower end. The section E is first cast. Afterward the clamping-section F is cast around the base of the section 55 E, and the metal forms the ring R in the groove G, thus producing a swivel-joint.

The form of the lower face of the swivel-plate F is shown in Fig. 1, in which the notches b' b' in each of the projecting sides is designed to 60 fit over the upper edge of the saw-blade H.

In order to operate my improved ferrule, the saw H is inserted in the clamping-loop I. The handle A is then turned until the screw P of the loop is run up in the nut D and the back 65 edge of the saw H enters the notches b' b' of the swivel-plate, where the saw is held fast by further screwing the nut D of the handle on the screw P. The handle A and ferrule-section 70 E turn freely on the ring R of the section F.

What I claim as new, and desire to secure by Letters Patent, is—

1. In a saw-handle, the combination, with the ferrule-section E, having a groove, G, around its lower end, of the saw-clamp section 75 F, having ring R cast in the groove G, forming therewith a swivel-joint, substantially as shown and described.

2. In a saw-handle, the combination of the ferrule-section E, having socket above for the 80 end a of the handle, recess b below for the passage of the saw-loop I, and annular groove G around its lower end, and the clamp-section F, having ring R cast in the groove G, forming a swivel-joint, and provided on its under surface 85 with notches b' b', with the handle A, having opening B, fixed nut D, and screw P, provided with saw-holding loop I, whereby when the handle is turned in one direction the said screw is run up through the fixed nut until the back 90 of the saw held in the loop at the end of the screw is firmly engaged with the lower notched surface of the clamping-section or swivel-plate F, substantially as shown and described.

In testimony whereof I have signed my name 95 to this specification in the presence of two subscribing witnesses.

ANDREW J. DOANE.
